UNITED STATES PATENT OFFICE

166,096

FOOD AND DRINK BAR UNIT OR SIMILAR ARTICLE

William S. Milner, Chicago, Ill.

Application January 26, 1950, Serial No. 7,475

Term of patent 7 years

(Cl. D2—3)

To all whom it may concern:

Be it known that I, William S. Milner, a citizen of the United States, residing at Chicago, in the county of Cook and State of Illinois, have invented a new, original, and ornamental Design for a Food and Drink Bar Unit or Similar Article, of which the following is a specification, reference being had to the accompanying drawings, forming part thereof.

Fig. 1 is a front perspective view of a food and drink bar unit showing my new design.

Fig. 2 is a rear perspective view thereof.

I claim:

The ornamental design for a food and drink bar unit or similar article, substantially as shown.

WILLIAM S. MILNER.
